STARTING MEANS

Joseph Jandasek, Cicero, Ill.

Application March 31, 1937, Serial No. 133,943

2 Claims. (Cl. 123—179)

This invention relates to superchargers, and more particularly to multi-stage superchargers employed primarily to supply a combustible mixture to engines.

It has been found in the use of supercharged engines that at relatively slow speeds, the engine does not drive the supercharger at sufficiently high speed to supply the degree of pressure desired for such purposes.

Superchargers as utilized in the past have been of a relatively complicated design, and required considerable space for installation. For these reasons superchargers have not been employed to the extent which their utility would indicate that they could be used to advantage.

An object of this invention is therefore to provide an efficient engine supercharger which can be manufactured economically.

A further object is to interpose a supercharger between the carburetor and the intake manifold of an engine to thoroughly mix the carbureted mixture and supply it to the engine at desirable positive pressures.

Another object of the invention is to provide a multi-stage supercharger driven by the engine crankshaft at increased speed.

Yet a further object is to provide means for driving a supercharger to develop a predetermined pressure in the engine manifold before the engine is started.

A further object is to provide a novel supercharger formed of stamped sections welded together which may be manufactured economically.

A still further object is to provide a novel seal for a supercharger shaft and bearing.

Another object is to provide novel means for charging a uniflow two-cycle engine wherein a combustible mixture under pressure is admitted to the engine cylinder through spaced ports surrounding the cylinder.

Yet a still further object of the invention is to provide an inexpensive small supercharger assembly, which may be driven through speed increasing means operably connected to the accessory drive mechanism of automotive engines.

A further object is to provide a multi-stage supercharger having alternately spaced radially disposed impeller and guide wheel blades formed of inexpensive stampings.

Other objects and advantages of this invention will be apparent from the following detailed description, considered in connection with the accompanying drawings submitted for purposes of illustration only and not intended to define the scope of the invention, reference being had for that purpose to the subjoined claims.

In the drawings wherein similar reference

characters refer to similar parts throughout the several views:

Figure 1 is a vertical section of an engine and supercharger assembly embodying the present invention;

Figure 2 is a diagrammatic view illustrating a supercharger drive for supplying a supercharged combustible mixture to the engine for starting purposes;

10 Fig. 2a is a detail sectional view of one form of apparatus for operatively connecting the supercharger to a driving means therefor.

Figure 3 is a vertical section of a multi-stage supercharger driven through a turbo clutch;

15 Figure 4 is a plan view of the impeller shown in Figure 3;

Figure 5 is a view taken on the line 5—5 of Figure 4;

20 Figure 6 is a sectional view taken on the line 6—6 of Figure 4;

Figure 7 is a view taken on the line 7—7 of Figure 3 showing a portion of one element of the turbo clutch;

25 Figure 8 is a view similar to Figure 6 showing a modified form of impeller vane construction;

Figure 9 is a view similar in some respects to Figure 5 showing a modified reinforced vane construction;

30 Figure 10 is a view similar to Figure 3 showing a modified form of a multi-stage supercharger;

Figure 11 is a plan view of one of the impeller or guide wheel vanes shown in Figure 10;

35 Figure 12 is a view taken on the line 12—12 of Figure 10;

Figure 13 is a part sectional view showing a supercharger driven by speed increasing means operably connected to the accessory drive mechanism of an automotive engine;

40 Figure 14 is a vertical section of a modified form of a multi-stage supercharger driven through novel speed increasing means; and

Figure 15 is a plan view of one desirable form of speed increasing means for driving a supercharger.

45 Referring more particularly to Figure 1 there is shown, for purposes of illustrating this invention, a supercharger designated by the reference numeral 2 driven through speed increasing means 4 operably connected to a crank shaft 6 of an engine designated as a whole by the reference character 8. The supercharger 2 is provided with an inlet passage 10 communicating with a carburetor 12 having an air inlet control valve 14 and a main fuel supply nozzle 16.

50 The supercharger illustrated is of the multi-stage type having alternately spaced radially disposed impeller and guide wheel blades 18 and 20 respectively. A collecting passage 22, surrounding the impeller and guide blades 18 and

20, receives the compressed carbureted mixture, and delivers it through a manifold riser 24 having a throttle valve 26 positioned therein. A manifold riser 24 communicates with an annular passageway 28 surrounding a cylinder 30 of the engine 8. The cylinder 30 receives a compressed mixture from the annular passageway 28 through a plurality of spaced ports 32 extending through the side walls of the cylinder 30.

A piston 33 operably connected to the crank shaft 6 by means of a connecting rod 34 compresses the charge admitted to the cylinder 30. The products of combustion may be exhausted from the cylinder 30 by means of the exhaust passageway 36 controlled by an exhaust valve 38 controlled by any desired timing mechanism, such for example, as the rocker arm 40 connected with the push rod 42 controlled by a cam 44 positioned on the crank shaft 6.

The operation of this device is as follows. The carburetor 12 provides a combustible mixture of fuel admitted through the main fuel jet 16 and air passing the choke valve 14 to the inlet 10 of the supercharger 2. The first stage impeller 18 accelerates the combustible mixture admitted, and delivers it to the first stage guide wheel 20 wherein the velocity of the mixture is decreased, and the velocity energy is transformed into pressure energy. The mixture is then admitted to the second stage impeller 18 radially outwardly spaced with reference to the first stage guide wheel 20, wherein the velocity of the mixture is accelerated, and the mixture is passed to a second stage guide wheel 20 radially outwardly spaced with reference to the second stage impeller. The second stage guide wheel converts the velocity energy into pressure energy, and delivers the mixture to the collecting passage 22.

This compressed combustible mixture is passed to the manifold riser 24 past the throttle valve 26 to the annular passageway 28 which communicates with the cylinder 30 by way of the spaced ports 32 when the piston 33 is moved by the connecting rod 34 to a position to uncover the spaced ports 32. This method of charging the engine is particularly advantageous because of the fact that compressed mixture is admitted at spaced points surrounding the cylinder whereupon scavenging of the products of combustion from the cylinder 30 through the exhaust outlet 36 is facilitated.

Fuel for idling purposes, when the throttle valve 26 is closed is supplied through a fuel passageway 46 having a check valve 48 therein, and diluting air is supplied through a passageway 50 communicating with the collecting passage 22. Additional fuel for acceleration purposes may be supplied through a fuel duct 52 interconnecting the collecting passage 22 and an acceleration well in the carburetor 12, check valve 54 being provided in the duct 52.

A starter 56 may be employed to drive the supercharger shaft 58 through a one-way clutch 60. It will be observed that this starting device drives the supercharger 2 at relatively high speed, and drives the engine 8 at a slower speed due to the speed varying means 4 interposed between the supercharger and the engine. Figure 2 shows an assembly wherein the supercharger 2 may be driven by an auxiliary starter 62 operably connected thereto by means of a one-way clutch 64. A main starter 66 is employed to start the engine 8. A one-way clutch 64a is interposed between the supercharger 2 and the engine 6, which clutch is so disposed that rota-

tion of the supercharger 2 in a predetermined direction will not be communicated to the engine, whereas rotation of the latter will be communicated to the supercharger, when the engine rotates in said direction. Clutch 64 is illustrated in cross-section in Fig. 2a and is constituted, for example, by a central shaft or driving member having a surrounding driven member. The shaft is rotated by starter 62. The driven member is provided with serrations upon an inner periphery thereof in which clutch balls are movable to operatively interconnect the driving and driven members when rotation occurs, for example, in a clockwise direction but not in the opposite direction. In this embodiment the supercharger 2 may be driven by the auxiliary starter 62 to supply a compressed combustible mixture to the engine 8 before the engine starter 66 is actuated to start the engine. Starting of the engine is thus facilitated since a greater compression ratio is possible when this device is employed.

Figure 3 illustrates a modified form of a multiple-stage supercharger driven through a turbo clutch 70, having impeller and turbine runner elements 72 and 74 respectively. As illustrated more clearly in Figure 7 the turbine runner is formed with vanes 80 and 82 respectively fixed thereto, and the impeller may be formed with vanes 76 and 78. The impeller 70 is fixed to a driving shaft 84, and the turbine runner 74 is fixed to a driven shaft 86, the driven shaft 86 having the first and second stage impeller discs 88 and 90 fixed thereto. A housing 92 surrounds the driven shaft 86 and has the first and second stage guide wheels 94 and 96 respectively fixed thereto. A carburetor 98 supplies a combustible mixture to a supercharger inlet 100. The combustible mixture admitted through the inlet 100 is passed through a directing screw 101, and is then passed to the first stage impeller 88, which accelerates it and drives it outwardly. The first stage guide wheel 94 receives the accelerated mixture from the first stage impeller 88, and transforms the velocity energy into pressure energy and directs the compressed fluid to the second stage impeller 90 which again accelerates the fluid and directs it to the second stage guide wheel 96, wherein the velocity energy is again converted into pressure energy. The compressed mixture is then directed to an engine manifold through the outlet passage 103.

Attention is directed to the bearing assembly between the shaft 86 and the housing 92. It will be observed that ball bearings 105 are employed, and that a collar 107 projects upwardly at the end of the bearing. A shield 109 projects down over the collar 107. Oil supplied to lubricate the bearing 105 is driven outwardly by centrifugal force, and overlies the space between the collar 107 and the shield 109. This shield prevents air from entering along the shaft to dilute the carbureted mixture supplied from the carburetor 98 to the first stage impeller 88.

As more clearly illustrated in Figures 4, 5 and 6 the impeller and guide wheel members may be formed of a flat disc 111 having blades 113 spot-welded or otherwise fixed thereto. It will be observed that the blades 113 are wider nearer the shaft 86, and converge toward the outer edge of the disc 111, and that the space between the blades 113 is less nearer the shaft 86, thereby forming a divergent channel between adjacent blades 113. Impeller and guide wheel members formed in this manner may be manufactured very economically, and the space required to in-

stall such a supercharger is comparatively small.

The channel shaped blade structure 115 illustrated in Figure 8, may if desired be employed in place of the channel shaped blade structure 113 shown in Figure 6. This blade structure embodies greater strength than the blades 113.

If desired an auxiliary bracing disc 117 fixed at one end to the disc 111 may be employed to strengthen the disc 111, as illustrated in Figure 9.

Attention is directed to the fact that where the turbo clutch drive mechanism illustrated in Figure 3 is employed there is no danger of breaking the supercharger drive shaft upon sudden deceleration of the engine with which the supercharger is employed since the turbine runner 14 may revolve with reference to the impeller 12 whereupon the inertia built up in the impeller and guide wheel vanes of the supercharger may be gradually dissipated, thereby obviating any possibility of subjecting the supercharger driving mechanism to critical overloads. Figure 10 illustrates another modified form of supercharger wherein the fluid to be compressed is admitted through an inlet passage 121, and is directed to a first stage impeller 123, then to a first stage 25 guide wheel 125, from there to a second stage impeller 127, and later to a second stage guide wheel 129 communicating with an outlet passage 131. It will be observed that the first and second stage impeller 123 and 127 are carried and driven by a disc 135 fixed to a driving shaft 137. The first and second stage guide wheels 125 and 129 are carried by a disc 139 fixed with reference to a housing 141.

The impellers and the guide wheels may be 35 formed of spaced discs 143 and 145 having apertures 147 therein, as more clearly illustrated in Figure 12. The blades of the impeller and guide wheels may be formed of flat plates 149 having locking tabs 151 carried thereby as more clearly shown in Figure 11. To assemble the impeller or guide wheels the discs 143 and 145 are positioned in spaced relation and the tabs 151 of the blades 149 inserted through the apertures 147 in the discs 143 and 145. The locking tabs 151 are then bent over to securely lock the discs 143 and 145 together whereupon the blades 149 are held in the desired assembled relation.

The embodiment of the invention illustrated in Figure 13 is similar in many respects to the embodiment illustrated in Figure 1, corresponding parts having therefore been given corresponding reference numerals with the addition of 100. It will be observed that the carburetor 112 supplies a combustible mixture to the inlet 110 of the supercharger 102. The velocity of the combustible mixture thus supplied is accelerated by the impeller 113 which delivers the accelerated mixture to the guide wheel 120. The guide wheel 120 converts the velocity energy into pressure energy, and delivers the compressed fluid to the collecting passage 122, communicating with the manifold riser 124, leading to the cylinders of the engine.

Attention is directed to the fact that in this embodiment of the invention the supercharger 102 may be driven by an accessory drive shaft 155. The shaft 155 may be driven by V belts passing over the pulleys 157, or in any other desired manner, to drive the bladed fan 159, a generator 161, and any other desired accessories. A universal joint 163 interconnects the shaft 155 and a stub shaft 165 which drives the supercharger through the speed increasing means 104.

The illustrated speed increasing mechanism, as more clearly shown in Figures 13 and 15, includes a spider member 167 having the driving fingers 169 fixed thereto. The driving fingers 169 engage hollow rollers 171 frictionally engaged between a hardened ring 173 and a hardened roller 175 carried by the supercharger drive shaft 155.

In the operation of this device, the accessory drive shaft 155 drives the stub shaft 165, through the universal joint 163. The spider member 167 fixed to the stub shaft 165 drives the fingers 169 which rotate the rollers 171 against the hardened ring 173, and drive the hardened roller 175. The roller 175 is thus driven at a much higher speed than the speed of the driving shaft 155.

This supercharger drive mechanism may be incorporated in automotive vehicles of conventional design, and particularly those of the V type wherein a single centrally disposed intake manifold is employed to supply carbureting mixture to the cylinders of the engine.

The embodiment of the invention illustrated in Figure 14 is similar in some respects to that illustrated in the other figures. It will be observed that in this embodiment of the invention the supercharger is driven by a double chain 177 operating on sprocket wheels 179 which drive the supercharger shaft 181 at increased speed through the speed increasing gears 183 interposed therebetween. In this embodiment it should be noted that a longitudinally contracted driving mechanism is provided which drives the supercharger impellers 185 and 187 at increased speed. The fluid to be compressed is admitted to the supercharger through an inlet 189 communicating with the first stage impeller 185 through a passageway 191. The impellers 185 and 187 increase the velocity of the fluid, and the guide wheels 193 and 195 convert the velocity energy into pressure energy and deliver the compressed fluid to the manifold 197 of the engine.

It will be understood of course that a greater number of impellers and guide wheels may be employed if desired to deliver the compressed fluid at the desired pressure.

While the invention has been illustrated and described with particular reference to several desirable embodiments, it is to be understood that many changes can be made in the particular combinations or mechanisms employed without departing from the spirit of the invention as defined by the following claims.

I claim:

1. In an internal combustion engine, a main starting mechanism for the engine, a supercharger, a one-way clutch for operatively interconnecting the engine and supercharger, auxiliary means for actuating the supercharger, and a one way clutch between the supercharger and auxiliary means, the first-named clutch adapting the auxiliary means for driving the supercharger before the main starting mechanism is actuated.

2. In an internal combustion engine, means for actuating the engine to start same, a supercharger, a one-way clutch for operatively interconnecting the supercharger and engine, auxiliary means for driving the supercharger, and a one way clutch between the supercharger and auxiliary means, the first-named clutch adapting the auxiliary means for driving the supercharger prior to actuation of the first named means and adapting the supercharger for actuation by the engine after the latter is started.

JOSEPH JANDASEK.
